UNITED STATES PATENT OFFICE.

DANIEL W. LAYMAN, OF INDIANAPOLIS, INDIANA.

DISPENSING TOP FOR CONTAINERS.

Application filed April 19, 1924. Serial No. 707,601.

To all whom it may concern:

Be it known that I, DANIEL W. LAYMAN, a citizen of the United States, and a resident of Indianapolis, county of Marion, and 5 State of Indiana, have invented a certain new and useful Dispensing Top for Containers; and I do hereby declare that the following is a full, clear, and exact description thereof, reference being had to the accompanying drawings, in which like numerals refer to like parts.

This invention pertains to a dispensing cap or top for containers, and particularly for use on collapsible tubes containing paste 15 or the like, but which may also be readily adapted for use on cans or similar tubes of paste or powder containers.

The object of the invention is to provide a sliding member for controlling the orifice 20 through which the material may be dispensed, in such fashion that the usual type of screw cap will be avoided with the consequent possibility of losing the same.

The principal feature of the invention resides in the construction and mounting of the sliding valve or closure member on the top of the container, wherein the maximum degree of efficiency and cheapness in construction may be obtained, and it may be 30 readily assembled.

Another feature of the invention resides in the wedging arrangement of the dove-tail tongue and groove sliding joint, whereby the valve may be slightly wedged in closed 35 position sufficient to hold it against accidental opening. This also may be accomplished by roughening the engaging parts of the tongue and groove.

The full nature of the invention will be 40 understood from the accompanying drawings and the following description and claims:

In the drawings, Figure 1 is a plan view looking down on the top of the container 45 showing the valve closure in closing position. Fig. 2 is a central vertical section through the top of the container showing the valve closure in open position. Fig. 3 is a section taken on the line 3—3 of Fig. 50 2. Fig. 4 is a side elevation of the top of the container.

In the drawings there is shown what may be a paste tube 10 or any other type of container, such as a box or can, having an 55 annular metal top 11 of reduced diameter and connected with the tube 10 by the taper-

ing of conical neck portion 12. The top 11 is provided with a discharge opening 13 provided with a slot 14. The exposed surface of the top 11 is provided with a diametrically extending dove tailed groove 15 in which is dove tailed, so as to be slidably mounted therein, a valve or closing member 16. Said valve or closing member is provided with a transverse slot 17 adapted to 60 register with the dispensing slot 14 when the valve is moved to one position, as shown in Fig. 2. When the valve is moved to the position, as shown in Fig. 1, the slots 14 and 17 are out of registry so as to prevent 65 the escaping or dispensing of the contents of the container.

The valve member is so arranged with respect to the top 11 that the upper surface of each of them are flush and in the same 70 plane, the dove tailed tongue and groove arrangement securely holding them in slideable engagement. The valve member is provided on one end with an upper or vertical projection 18 adapted to act as a finger hold 75 for facilitating the operation of the valve by the user. However, this is not necessary for the mechanical working of the valve member. The beveled side flanges of the dove-tailed portion of the valve member 80 are slightly widened toward one end, preferably the end bearing the upright projection 18 so that upon closing the valve there may be a slight wedging action which will frictionally hold the valve in closed position. In addition to the above-mentioned 85 widened projection, there are oppositely disposed lateral projections 19 so arranged as to engage the adjacent side of the cap 11 for limiting the sliding movement of the valve 90 to closed position. After the valve has been positioned within the top, the opposite end thereof from the projection 18, which comprises the tongue 20, is bent downwardly to provide a stop and limit the movement of 95 the valve in the opposite direction, as well as the thumb piece for pushing the valve into open position. After the tongue 20 has been bent downwardly into position, as shown, it will be obvious that the valve 100 is located in slideable relation with the top 11 so that it cannot be removed therefrom and will not disengage the same unless the tongue 20 is again bent upwardly. Each 105 side of the annular cap 11 is provided with a recess 21 for receiving the tongue 20, and into which said tongue engages in limiting

the movement of the valve, whereby said tongue, when in that position, will be within the periphery of the top and out of the way.

5 Whereas the top is shown herein as being annular, it is obvious that it may be square without effecting this invention, and that the slots may be of any desired shape or configuration. Furthermore, if desired, 10 there may be substituted for the upwardly extending projection or the finger-hold 18, a downwardly extending tongue 20, as shown. This arrangement would provide 15 a tongue 20 on both ends of the valve for limiting its sliding movement in both directions and retaining the valve in place.

The invention claimed is:

A dispensing device comprising a neck with a dispensing outlet therethrough, a 20 flat top for said neck having an opening

therein communicating with the interior of said neck, the outer face of said top having a relatively wide dovetailed groove extending entirely across the same, a plate slidable in said groove and having its outer face 25 flush with the corresponding face of the said top, widened portions at the edges of said plate at one extreme end thereof to frictionally bind within said groove to positively limit the movement of the said plate 30 in one direction, and to frictionally hold the same against retraction, and the said plate having an opening therein to register with the opening in the top when the plate has reached its limit of movement in the opposite 35 direction.

In witness whereof, I have hereunto affixed my signature.

DANIEL W. LAYMAN.
